(57) **CLAIM**

The ornamental design for a bird spike with base and prongs, as shown and described.

DESCRIPTION

FIG. 1 is a top, front, right side perspective view of a bird spike with base and prongs.

FIG. 2 is a front elevation view of the bird spike with base and prongs of FIG. 1.

FIG. 3 is a right side elevation view of the bird spike with base and prongs of FIG. 1.

FIG. 4 is a top plan view of the bird spike with base and prongs of FIG. 1.

FIG. 5 is a bottom plan view of the bird spike with base and prongs of FIG. 1; and,

FIG. 6 is a top, front, right side perspective view of the bird spike with base and prongs of FIG. 1.

The broken lines in FIG. 6 depicting additional bird spikes in a stack form no part of the claimed design.
